UNITED STATES PATENT OFFICE.

WILLIAM EVENSEN, OF CHICAGO, ILLINOIS, ASSIGNOR TO THE GOSS PRINTING PRESS COMPANY, OF CHICAGO, ILLINOIS, A CORPORATION OF ILLINOIS.

DRIVING MECHANISM.

1,257,830.

Specification of Letters Patent.

Patented Feb. 26, 1918.

Application filed June 12, 1917. Serial No. 174,249.

To all whom it may concern:

Be it known that I, WILLIAM EVENSEN, a citizen of the United States, and a resident of Chicago, in the county of Cook and State 5 of Illinois, have invented certain new and useful Improvements in Driving Mechanisms, of which the following is a specification, reference being had to the accompanying drawings.

10 My invention relates to driving mechanisms and particularly to a form of driving mechanism adapted for use with printing presses. It is one of the principal objects of my invention to provide a form and arrangement of driving parts comprising a clutch through which the power may be applied at low speed, such clutch being of a type adapted to take hold immediately without slippage when power is to be transmitted there- 15 through, thereby preventing any tendency of the press being driven to first choke and then start suddenly, as would be the case if there were any appreciable lost motion in the connections between the press and the source 20 of power. It is another object of my invention to provide a mechanism of this type which shall be substantially noiseless at all stages of the operation of the press. It is another object of my invention to improve 25 driving mechanisms of this type in sundry details hereinafter pointed out. The preferred means by which I have accomplished my several objects are illustrated in the drawings and are hereinafter specifically 30 described. That which I believe to be new and desire to cover by this application is set forth in the claims.

In the drawings:

Figure 1 is a top or plan view of a driving mechanism embodying the preferred form of my invention;

Fig. 2 is an enlarged detail, being an enlarged sectional view taken substantially on line 2—2 of Fig. 1; and

Fig. 3 is a horizontal sectional view 45 through the parts shown in Fig. 2, being taken substantially on line 3—3 of said figure.

Referring to the several figures of the drawings in which corresponding parts are indicated by the same reference characters,—

10 indicates a drive shaft revolubly mounted in bearings 11 of any suitable type adapted

to be driven by a motor 12 suitably connected therewith. The shaft 10 has revolubly mounted thereon a large gear 13 from which power is to be transmitted through any suitable train of mechanism to a printing press or any other mechanism to be driven. The 55 gear 13 is adapted to be connected with the shaft 10 so as to rotate therewith by means of a clutch mechanism 14 of any suitable type which is adapted to be thrown into and out of operation by means of a shifting lever 60 15 having operative engagement with a groove 16 in a slidably mounted clutch member 17. When the lever 15 is in the position shown in Fig. 1 the clutch 14 is maintained in operation for causing the gear 13 to rotate with the shaft 10. When the lever 15 is given a stroke in the direction away from the gear 13, the toggle levers 18 of the clutch are straightened more or less relative to each other, serving to throw the 70 75 clutch out of operation.

The shaft 10 is also operatively connected with the gear 13 through the medium of a train of mechanism by which the gear 13 can be driven at a comparatively very much 80 slower rate of speed. This mechanism comprises a pinion 19 fixedly mounted upon the shaft 10 meshing with a gear 20 which is revolubly mounted upon a shaft 21 journaled in bearings 22 alongside of the shaft 10. The shaft 21 is adapted to be connected with a rotary member 23 by means of a clutch 24 similar to the clutch 14. The clutch 24 is adapted to be thrown into operation by means of a lever 25 engaging a 90 groove 26 in a clutch member 27, a movement of the member 27 longitudinally of the shaft 21 serving through the toggle arms 28 to throw the clutch 24 into and out of operation as will be readily understood. The 95 shaft 21 is connected with the gear 13 by means of a pinion 29 meshing with such gear.

The train of mechanism for connecting the shaft 10 with the gear 13 through the 100 medium of the shaft 21 and its coöperating parts comprises clutch connections between the gear 20 and the rotary member 23. These connections comprise a drum or collar 30 keyed or otherwise firmly secured 105 upon the hub 31 of the gear 20, the drum 30 being located adjacent to the rotary member 23 as is best shown in Fig. 3. A plu-

rality of friction shoes 32 of any suitable type are pivotally mounted upon the inner ends of links 33 which in turn are pivotally mounted upon the rotary member 23 by means of pins or bolts 34. Springs 35 are connected to the links 33 respectively and to the rotary member 23, such springs 35 having a tendency to draw the links 33 toward their radial positions, serving to bring the shoes 32 into contact with the periphery of the drum 30. The periphery of the drum 30 and the engaging faces of the shoes 32 are adapted to be of any appropriate material and form so as to produce a proper frictional engagement between the contacting surfaces so that when the drum 30 is rotated in clockwise direction in Fig. 2 the rotary member 23 will be caused to rotate in the same direction therewith. In the construction shown, the shoes 32 are provided with friction facings 32^a of leather or other suitable material, and the drum 30 is corrugated on its face to facilitate the gripping action. While the strength of the springs 35 is such as to hold the shoes 32 normally in position to be immediately operative for causing the rotation of the rotary member 23 upon the rotation of the drum 30 in clockwise direction in Fig. 2, such springs 35 are not of such a strength as to cause a rotation of the drum 30 in clockwise direction when power is applied to the rotary member 23 for rotating it in clockwise direction in said figure independently of the drum 30.

With the motor 12 causing a rotation of the shaft 10 in the direction indicated by the arrow thereon in Fig. 1, the pinion 19 will be driven in the same direction, causing a rotation of the gear 20 and the hub 31 in the opposite direction as indicated by the arrow on said hub in said figure. With the clutch 14 out of operation by reason of a proper manipulation of the lever 45 15, and with the clutch 24 in operation, power will then be applied from the hub 31 and drum 30 through the shoes 32 and links 33 to the rotary member 23 and through the clutch 24 to the shaft 21 to drive such shaft in the direction indicated by the arrow thereon in Fig. 1, such motion being transmitted through the pinion 29 to the gear 13 for driving such gear 13 in the direction indicated by the arrow upon the clutch mechanism 14 in said figure. When it is desired to speed up the driving of the printing press or other machine operatively connected with the gear 13 as above described, this is accomplished by throwing the clutch 14 into operation, serving to connect the gear 13 directly with the shaft 10 so as to cause such gear 13 to rotate at the same speed as that of the motor 12 instead of at the comparatively much slower speed 65 when the power is applied through the step-

down gearing 19-20 and 29-13. When the gear 13 is thus driven at high speed, the pinion 29 and the shaft 21 will be driven at a comparatively higher speed, as will be readily understood, serving to rotate the rotary member 23 at a very high speed in the direction indicated by the arrow upon the hub 31 in Fig. 1—that is to say, in the direction indicated by the arrow adjacent to the rotary member 23 in Fig. 2. Immediately upon the application of power through the clutch 14, the rotary member 23 will begin to rotate in clockwise direction in Fig. 2 independently of the drum 30, the springs 35 being adapted to yield as above described to permit the loosening of the shoes 32 upon the drum 30. As the clutch 14 tightens, serving to increase the speed of rotation of the rotary member 23, the shoes 32 are caused to move outward by centrifugal force 85 against the action of the springs 35 out of contact with the drum 30. In case the clutch 24 is then thrown out of operation so as to disconnect the rotary member 23 from the shaft 21, the high speed driving of the rotary member 23 will cease, and the springs 35 will again draw the shoes 32 into contact with the drum 30 whereupon the rotary member 23 will again begin its slow speed rotation with the gear 20.

When the press is being driven at high speed, as above described, and it is desired for any reason to change to the low speed driving, the power for continuing the driving of the press at the low speed is applied immediately without any lost motion through the medium of the friction shoes 32 just as soon as the press is slowed down to its normal slow speed rotation, the shoes 32 being brought into loose contact with the drum 30 by reason of the slowing down of the rotary member 23 some time in advance of the beginning of the application of power through the shoes. The press is thus assured against any possible falling below the normal slow speed driving and against any possible choking or sudden starting upon the transfer from the high speed drive to the low speed drive. Moreover, it is plain that there can be no abnormal slowing down or choking of the press upon a change from the low speed driving to the high speed driving, since the high speed driving mechanism is thrown into operation without a prior disconnection of the low speed driving mechanism. With the press being run smoothly and evenly in this manner, a change from the high speed to the low speed driving or from the low speed to the high speed driving can be accomplished without any substantial danger that the web shall be snapped by reason of the change. Inasmuch as this feature is very important in printing press work, it will be seen that my invention is peculiarly adapted for use with 130

printing presses, but it will be understood that I do not wish to limit myself to that particular use exclusively.

- So far as I am aware, I am the first in
- 5 the art to provide a driving mechanism comprising a rotary drum, and a rotary member journaled upon the axis of the drum and provided with one or more friction shoes movably mounted thereon and adapted to
  - 10 operatively engage the outer periphery of the drum, whether or not such shoes are provided with friction facings of leather or other yielding material, and whether or not such drum is corrugated as in the construction shown in the drawings, and my claims are to be construed accordingly.
  - 15

What I claim as my invention and desire to secure by Letters Patent, is—

1. In a driving mechanism, the combination of a drum, means for rotating said drum in one direction, a rotary member journaled upon the axis about which said drum rotates, a friction shoe adapted to be brought into engagement with the periphery of said drum and adapted when in operative engagement to drive the rotary member in the same direction, and other means for rotating said rotary member in the same direction at a higher speed, serving to carry said friction shoe out of operative engagement with the drum.
- 20
- 25
- 30

2. In a driving mechanism, the combination of a drum, means for rotating said drum in one direction, a rotary member journaled upon the axis about which said drum rotates, a friction shoe adapted to be brought into engagement with the periphery of said drum and adapted when in operative engagement to drive the rotary member in the same direction, and other means for rotating said rotary member in the same direction at a higher speed, serving to cause said friction shoe to move outward by centrifugal force out of operative engagement with the drum.
- 35
- 40
- 45

3. In a driving mechanism, the combination of a drum, means for rotating said drum in one direction, a rotary member journaled upon the axis about which said drum rotates, a friction shoe adapted to be brought into engagement with the periphery of said drum and adapted when in operative engagement to drive the rotary member in the same direction, and other means for rotating said rotary member in the same direction at a higher speed, serving to move the friction shoe outwardly from engagement with the drum.
- 50
- 55
- 60

4. In a driving mechanism, the combination of a drum, means for rotating said drum in one direction, a rotary member journaled upon the axis about which said drum rotates, a friction shoe movably mounted on said rotary member adapted to be brought
- 65

ery of the drum and adapted when in operative engagement to drive the rotary member in the same direction, and other means for rotating said rotary member with the friction shoe carried thereby in the same direction at a higher speed serving to carry said friction shoe by centrifugal force outward out of operative engagement with the drum.

5. In a driving mechanism, the combination of a drum, means for rotating said drum in one direction, a rotary member journaled upon the axis about which said drum rotates, a friction shoe movably mounted on said rotary member adapted to be brought into operative engagement with the periphery of the drum and adapted when in operative engagement to drive the rotary member in the same direction, yielding means tending to hold said friction shoe in operative engagement with said drum, and other means for rotating said rotary member with the friction shoe carried thereby in the same direction at a higher speed serving to carry said friction shoe outward by centrifugal force against the action of said yielding means out of operative engagement with the drum.

6. In a driving mechanism, the combination of a drum, means for rotating said drum in one direction, a rotary member journaled upon the axis about which said drum rotates, a plurality of links pivotally mounted on said rotary member and extending toward the periphery of said drum, a plurality of friction shoes connected with the inner end portions of said links respectively and adapted to have operative engagement with said drum when said links are swung substantially into radial position, yielding means tending to swing said links into radial position for causing the friction shoes to rotate said rotary member with said drum, and other means for rotating said rotary member in the same direction at a higher speed serving to carry said friction shoes out of operative engagement with the drum.

7. In a driving mechanism, the combination of a drum, means for rotating said drum in one direction, a rotary member journaled upon the axis about which said drum rotates, a friction shoe adapted to be brought into engagement with the periphery of said drum and adapted when in operative engagement to drive the rotary member in the same direction, and other means for rotating said rotary member in the same direction at a higher speed, serving to cause said friction shoe to lag behind slightly relative to its operative position upon the rotary member and eventually to move outward by centrifugal force out of operative engagement with the drum.

8. In a driving mechanism, the combination of a rotary drum, a rotary member journaled upon the axis about which said drum

is adapted to revolve, a friction shoe mov-
ably mounted on said rotary member adapt-
ed to be brought into operative engagement
with the outer face of said drum and adapt-
ed when in operative engagement to lock
5 said drum and said rotary member against
rotation in one direction relative to each
other, and yielding means tending to hold
said friction shoe in operative engagement
10 with said drum.

9. In a driving mechanism, the combina-
tion of a drum provided with longitudinally-
extending corrugations on its outer face, a
15 rotary member journaled upon the axis
about which said drum is revolvably mounted,
a friction shoe movably mounted on said
rotary member and provided with a fric-
tion facing of yielding material adapted to
20 be brought into operative engagement with
the corrugated face of said drum, and yield-

ing means tending to hold said friction shoe
in operative engagement with said drum
whereby either the drum or the rotary mem-
ber is adapted to drive the other in one di-
rection.

25

10. In a driving mechanism, the combina-
tion of a drum provided with longitudinally-
extending corrugations on its outer face, a
rotary member journaled upon the axis
about which said drum is revolvably mounted,
30 a plurality of friction shoes movably mount-
ed on said rotary member and each pro-
vided with a friction facing of yielding ma-
terial adapted to be brought into operative
engagement with the corrugated face of said
35 drum, and means for holding said shoes
yieldingly in operative contact with said
drum for rotating the drum in one direc-
tion.
